UNITED STATES PATENT OFFICE

135,557

DESIGN FOR A GLASS JELLY MOLD

Ben D. Levenson, Pittsburgh, Pa.

Application February 5, 1943, Serial No. 109,467

Term of patent 14 years

To all whom it may concern:

Be it known that I, Ben D. Levenson, a citizen of the United States, residing at Pittsburgh, in the county of Allegheny and State of Pennsylvania, have invented a new, original, and ornamental Design for a Glass Jelly Mold, of which the following is a specification, reference being had to the accompanying drawing, forming part thereof.

In the drawing:

Fig. 1 is a top plan view of a glass jelly mold, showing my new design;

Fig. 2 is a side elevation thereof;

Fig. 3 is an enlarged diagrammatic extended view of a portion of the inner design features, partly visible from the exterior; within the area indicated by the line III—III of Fig. 1;

Fig. 4 is an enlarged vertical partial cross-section on the line IV—IV of Fig. 2; and

Fig. 5 is a similar partial transverse section on the line V—V of Fig. 2.

I claim:

The ornamental design for a glass jelly mold, as shown and described.

BEN D. LEVENSON.
